[57] CLAIM

The ornamental design for an extruded bracket for a tilt tray sorting conveyor, as shown and described.

DESCRIPTION

FIG. 1 is a front perspective view of an extruded bracket for a tilt tray sorting conveyor showing my new design;

FIG. 2 is an end elevational view thereof, the opposite side elevational view being a mirror image;

FIG. 3 is a rear elevational view thereof; and,
FIG. 4 is a rear perspective view thereof.

FIG. 1

FIG. 2

FIG. 3

FIG. 4
